UNITED STATES PATENT OFFICE

2,080,355

REEL

Harry R. Geer, Westmont, Pa., assignor to Bethlehem Steel Company, a corporation of Pennsylvania

Application December 5, 1934, Serial No. 756,064

9 Claims. (Cl. 242—77)

My invention relates to reels and particularly to reels which are adapted to be used for wire, wire fencing or similar material.

One object of my invention is to provide a reel of the collapsible type, the parts of which may be easily stored and which may be easily assembled when required for use.

Another object of my invention is to provide a reel which is made up of a plurality of similar preformed parts.

A further object of my invention is to preform each member so that when a plurality thereof are assembled into a reel they will interlock with each other and the reel will be retained in its assembled condition without the use of any separate fastening means.

A still further object of my invention is to preform each member in such a manner so that when a plurality thereof are assembled into a reel a core is formed to provide an aperture which will permit the reel being mounted on a bar or the like so that it may be conveniently rotated when it is desired to coil the wire thereon or uncoil the wire therefrom.

The novel features of my invention will be more fully understood from the following description and claims taken with the drawing in which

Fig. 1 is a perspective view of a reel embodying the features of the present invention.

Fig. 2 is a perspective view of one of the members of the reel shown in Fig. 1.

Referring to the drawing, 15 designates my improved reel, which, as shown in the drawing, comprises four similar members 16, one of which is plainly shown in Fig. 2. As all of the members 16 are similar only one will be described.

The member 16 comprises a longitudinal body portion 17 and laterally disposed head portions 18 and 19 which are integral with the ends of the body portion. As both of the head portions are similar in all respects only one will be described. The head portion 18 comprises a looped portion 20, having an offset hook portion 21 at its end, a core portion 22, a hook engaging portion 23, which is preferably substantially straight as shown in the drawing, and a hook portion 24. A recess 25 is formed adjacent the hook portion 24 and the body portion 17 and provides means to receive the offset portion 21 of an adjacent loop portion 20 when the reel is in its assembled condition. The core portion 22 as shown in the drawing is of arcuate formation so that when the members 16 are assembled an

aperture will be provided to receive a round bar or the like for handling the reel.

One method of assembling the reel is to pass the head portions 18 and 19 of one member 16 between the head portions 18 and 19 of a second similar member 16, and hooking the portions 24 of the first-mentioned member over the portions 23 of the second member, and then passing the head portions 18 and 19 of a third member 16 intermediate the head portions 18 and 19 of the second mentioned member and hooking the portions 24 of that member over the portions 23 of the second-mentioned member and then passing the head portions 18 and 19 of the fourth member 16 between the head portions 18 and 19 of the third member 16 and over the head portions 18 and 19 of the first-mentioned member and hooking the portion 24 of the fourth member over the portion 23 of the third member and hooking the portion 24 of the first member over the portion 23 of the fourth member. The ends 21 are inserted in the recesses 25 before the hook portions 24 are in their final assembled relation with the members 23 and due to the shape of the ends 21 they are locked against displacement when the hook portions 24 are in their final assembled relation with the portions 23.

From the above it will be obvious that I have invented an improved reel which is preferably made up of identical parts which are easily stored, and which are easily assembled when required.

While I have shown my invention in but one form, I do not wish to be limited to the exact and specific details thereof, as shown and described but may use such modification in, substitutions for, or equivalents thereof, as are embraced within the scope of my invention, or as pointed out in the claims.

Having thus described my invention what I claim as new and desire to secure by Letters Patent is:

1. A reel, comprising a plurality of similar members, each of said members comprising a body portion and opposite head portions, each of said head portions comprising a looped end portion, a hook at the extremity of said looped end portion and a core portion intermediate said looped end portion and the body portion, and interlocking means integral with the head portions whereby the members are retained in assembled relation.

2. A wire reel comprising a plurality of like members, each of said members constituting a

- body portion and opposite head portions having looped end portions, and a core portion intermediate each looped end portion and the body portion.
5. A wire reel comprising a plurality of like members in interlocked relation, each of said members comprising a substantially straight body portion, and head portions, each of said head portions comprising a looped end portion, 10 a hook portion and a core member intermediate the looped end portion and the body portion.
4. A wire reel comprising a plurality of similar members assembled in interlocked relation, each of said members comprising a substantially straight body portion, and head portions, each of said head portions comprising a looped end portion, 15 a core portion, a substantially straight portion intermediate the looped end portion and the core portion and a hook portion intermediate the body portion and the core portion.
5. A wire reel comprising a plurality of similar members, each of said members constituting a body portion and opposite head portions, each of the head portions comprising a looped end portion, 20 a core portion intermediate the looped end portion and the body portion, a hook portion intermediate the body portion and the core portion and a hook engaging portion.
6. A wire reel comprising a plurality of similar members, each of said members constituting a body portion and opposite head portions, each of said head portions comprising a looped end por-

tion, a core portion, a hook engaging portion intermediate the looped end portion and the core portion, a hook portion intermediate the core portion and the body portion forming a recess intermediate the hook portion and the body portion and a hook portion adjacent the terminus of the looped end portion.

7. A wire reel, comprising four like members only, each of said members constituting a body portion and a head portion of said reel, said head portion comprising an integral core portion and an end portion extending beyond the core portion, and means adjacent the body portion and in spaced relation to the core portion to fasten the members in assembled relation.

8. A reel comprising a plurality of similar members, each of said members comprising a body portion and head portions, each of said head portions comprising a loop portion and a core portion, said core portion lying intermediate said loop portion and the body portion of said member.

9. A reel comprising a plurality of similar members, each of said members comprising a body portion and opposite head portions, the head portion of said member comprising an end portion extending beyond the body of the reel to provide a guard for material wound on said reel, and a core portion intermediate said end portion and the body portion integral with said portions.

HARRY R. GEER.
